United States Patent

Des. 240,266
Patented June 8, 1976

240,266

COIN OPERATED PHONOGRAPH

Robert A. O'Neil and Michael C. Wilson, Glen Ellyn, Ill.,
assignors to The Seeburg Corporation of Delaware,
Chicago, Ill.

Filed Aug. 13, 1974, Ser. No. 497,115

Term of patent 14 years

Int. Cl. D14—01

U.S. Cl. D56—4 R

FIG. 1 is a right front and right side perspective view of a coin operated phonograph showing our new design; FIG. 2 is a left side elevational view; FIG. 3 is a front elevational view; FIG. 4 is a top plan view; FIG. 5 is a rear elevation view; and FIG. 6 is a bottom plan view.

We claim:

The ornamental design for a coin operated phonograph, substantially as shown and described.
